UNITED STATES PATENT OFFICE.

HIRAM H. HIRSCH, OF PHILADELPHIA, PENNSYLVANIA.

METAL-FINISHING BRUSH.

SPECIFICATION forming part of Letters Patent No. 717,851, dated January 6, 1903.

Application filed April 18, 1902. Serial No. 103,551. (No model.)

To all whom it may concern:

Be it known that I, HIRAM H. HIRSCH, a citizen of the United States, residing at Philadelphia, county of Philadelphia, and State of Pennsylvania, have invented a certain new and useful Improvement in Metal-Finishing Brushes, of which the following is a specification.

My invention relates to a new and useful improvement in metal-finishing brushes, and has for its object to provide an apparatus composed of a series of loose revolving brushes which are adapted to strike the metallic surface to be finished, and thereby so prepare the surface that it will present an even dull finish resembling somewhat the finish given to brass by means of emery, but being much more pleasing to the eye, and this apparatus is used to great advantage in finishing the brass parts of metallic bedsteads.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a cross-sectional view showing the revolving brush acting upon a metallic tube, and Fig. 2 is a longitudinal view of the brush.

In the drawings, A and A' represent two disks secured rigidly to a shaft B, and between these disks and secured to the same extend pins or rods C, upon each of which are arranged loosely a series of eyes D, and in each of these eyes are secured a series of tufts of wire E, each tuft consisting of a number of strands of wire of different lengths bunched together.

In operation the shaft B is designed to be rotated at considerable speed, and in doing so the tufts of wire E will be thrown outward by centrifugal force, and by holding a metallic tube or other article within range of

the brush, so that the ends of the wire will 50 strike the surface of the metal lightly, the surface will be scratched or stippled by these wire brushes; but the contact between the wire and the metallic surface will be so slight that the scratches or stippling will all blend, 55 so as to give the appearance of an even surface. The eyes D in being secured loosely to the disks will not present a rigid resistance, and therefore the wire brushes will strike the metallic surface in the lightest possible manner.

The pins C are inserted in the disks by being passed entirely through the disk A' and into holes formed part way through the disk A. Then a third disk A² is secured outside 65 of the disk A', and these two disks are secured together by screws A³. Thus the pins C are held securely in place, but may be easily removed at any time to substitute new tufts of wire.

Of course I do not wish to be limited to the exact construction here shown, as slight modifications could be made without departing from the spirit of my invention.

Having thus fully described my invention, 75 what I claim as new and useful is—

In a device of the character described, a driving-shaft, two disks A and A' secured rigidly to the shaft, pins or rods carried by said disks and arranged concentrically with 80 the driving-shaft, said pins adapted to pass entirely through the disk A' and part way into the disk A, a disk A² secured to the outside of the disk A' for the purpose of holding the pins in place, a series of eyes pivoted 85 loosely upon each of the pins or rods, a series of tufts of wire secured to each of the eyes, said tufts consisting of a number of wires of different lengths bunched together, substantially as described and for the purpose specified.

In testimony whereof I have hereunto affixed my signature in the presence of two subscribing witnesses.

HIRAM H. HIRSCH.
